[57] **CLAIM**

The ornamental design for a container for liquid ink for a printing machine, as shown.

DESCRIPTION

FIG. 1 is a first perspective view of a container for liquid ink for a printing machine showing our new design;

FIG. 2 is a front elevational view of the container for liquid ink for a printing machine of FIG. 1;

FIG. 3 is a rear elevational view of the container for liquid ink for a printing machine of FIG. 1;

FIG. 4 is a right side elevational view of the container for liquid ink for a printing machine of FIG. 1;

FIG. 5 is a left side elevational view of the container for liquid ink for a printing machine of FIG. 1;

FIG. 6 is a top plan view of the of the container for liquid ink for a printing machine of FIG. 1;

FIG. 7 is a bottom plan view of the container for liquid ink for a printing machine of FIG. 1; and,

FIG. 8 is a second perspective view of the container for liquid ink for a printing machine of FIG. 1.
